UNITED STATES PATENT OFFICE.

CHARLES H. LEWIS, OF SYRACUSE, NEW YORK.

STEAM GENERATOR.

1,410,583.

Specification of Letters Patent. Patented Mar. 28, 1922.

Application filed March 9, 1921. Serial No. 450,852.

To all whom it may concern:

Be it known that I, CHARLES H. LEWIS, a citizen of the United States, residing at Syracuse, in the county of Onondaga and 5 State of New York, have invented certain new and useful Improvements in Steam Generators, of which the following is a specification.

This invention relates to improvements in 10 steam generators, and has for its object to provide a novel and simple boiler construction whereby steam at high tension may be generated readily and quickly by the consumption of a minimum of fuel. A further 15 object is to provide a boiler of the class which is entirely enclosed by an insulated casing, the latter being spaced from the boiler for affording a free and unrestricted passage for the products of combustion from 20 the bottom towards the top of the boiler. A further object is to provide a novel auxiliary water heater in the form of a hollow disc, which is positioned between the boiler and the source of heat, wherein relatively 25 small volumes of water may be heated and reduced to steam more readily and quickly than steam is generated in the main boiler shell; the steam generated by said disc being conducted by an independent conduit 30 directly into the top portion of the boiler. A further object is to provide a second and larger auxiliary water heater comprising a hollow annular part which is disposed beneath and supplies water and saturated 35 steam to the disc heater, and which communicates in a novel manner with the main boiler, for the circulation of water and steam therebetween. And a further object is to generally improve and simplify, as 40 well as to quicken the action of steam generators of the class.

This invention relates particularly to improvements in the devices shown and described in my pending application Serial 45 No. 392,356.

The various features of the parts of the invention will be understood from the detailed description which follows, and by reference to the accompanying drawings, 50 in which—

Figure 1 is a central vertical section taken on line 1—1 of Fig. 3. Fig. 2 is a reduced elevational view of the complete device. Fig. 3 is a horizontal section taken 55 on line 3—3 of Fig. 1. And Fig. 4 is a similar view taken on line 4—4 of Fig. 1.

In the drawings, 2 represents the usual annular base having a plurality of legs 2'. 3 is the usual cylindrical firebox, the lower end of which receives the top flange of the 60 base 2, to which it is secured by bolts 3'. Within the box 3 is disposed a gas or vapor burner 5, which furnishes heat for the boiler and related parts. The burner is preferably circular and is provided on its top- 65 side with a number of jet-burners 5'. Oil, gas, or any other suitable fuel may be used for producing the heat, and the fuel may be supplied by a pipe 6 (see Fig. 2). Further details of the burner are omitted 70 for the reason that they form no essential part of the invention.

Upon the casing 3 is mounted an annular part 7, having a depending flange 7', which telescopes and supports the open top-end of 75 the casing 3, the latter being secured in place by bolts 3^a. The hollow tubular casing 8 of the boiler proper is mounted upon the ring 7, and its top end is closed by a cap 8' which has a depending flange that 80 telescopes the casing and is held in place by bolts 8^a. The interior of the cap 8' is provided with a number of radial ribs 8^b, and has a central opening 8^c for the escape of the waste products of combustion. The 85 casing 8 is preferably lined with an insulation of asbestos 8^d, for conserving the heat which rises from the burner 5, during the operation of the generator.

The main boiler shell, comprises an up- 90 right cylinder 9, which is loosely disposed within and concentric to the jacket 8, the top end of the boiler preferably contacting the ribs 8^b for steadyng said end. This end of the boiler is preferably closed by a sunken 95 head 9', which is held in place by rivets 9^a, and tightly seals said end. The bottom end of the shell 9 is closed and sealed by a similarly shaped part 9^b, which bulges downwardly, and is secured to the shell by 100 rivets 9^c. The bottom 9^b is perforated centrally and threaded to receive a bushing 9^d and it is also provided with another perforation to receive a pipe 9^e, which comprises one of the water and steam circula- 105 tion members.

Near the top of the boiler-shell 9 are a number of perforations for facilitating the attachment of a steam outlet-pipe 10, a steam-gage 11, and a safety-valve 12. Midway in 110 the height of the shell 9 are two perforations 13' for the attachment of the usual water

gage or glass 13, and preferably opposite the water gage, are perforations which respectively receive a water supply-pipe 14, and a wash-out plug 15. A number of pet-cocks 5 (not shown), may be applied to a series of alining perforations 9^e.

An important and novel feature of the present invention consists of independent means for preheating relatively small portions or volumes of the water for quickening the generation, and at the same time materially increasing the tension of the steam, which will now be described:

16 represents an annular drum or coil, 15 preferably about the same diameter as the boiler-shell 9, which is disposed horizontally and in line axially with the boiler. The drum 16 is positioned directly above and concentric to the burner 5, and therefore is 20 the first to receive the heat from the gas flames. The drum is partially enclosed by the upper end of the casing 3, and has a free annular water space 16^a, and its body is reinforced by top and bottom ribs 16^a. 25 Around the top outer margin, the drum 16 is provided with upwardly projecting perforated lugs 16^b, which are secured to corresponding portions 7^a of the ring 7, by bolts 7^b. The drum 16 is so positioned that all of 30 the heat rising from the burner 5 is compelled to pass through the clear central opening or well 16^c. By this arrangement the greater portion of the heat from the relatively broad burner 5 is directed towards 35 and against the bottom and the peripheral surfaces of the drum, before the products of combustion finally pass upwardly through the well 16^c. This materially quickens the evaporation of the water in the drum, and 40 enables me to generate steam in a comparatively short space of time. The periphery of the drum 16 is preferably perforated at opposite points to receive extensions of the flow and the return pipes 14 and 9^e. This 45 arrangement of the piping affords a free and uninterrupted circulation of the water, between the shell of the boiler and the drum 16 during the evaporating period. The provision of the oppositely arranged pipes 9^e 50 and 14, one or the other of which performs the function of a by-pass, between the drum 16 and the boiler shell, tends to effectually relieve all resistance, which the back pressure of the steam usually exerts on a single 55 conductor (like that shown in my former application), to the flow or circulation of the water between the drum 16 and the shell 9, and therefore materially quickens the action of the present generator. The pipes 9^e 60 and 14 are provided with threaded openings which are shown closed by screw-plugs 9^x and 14^x, either of which may be removed and replaced by suitable supply and discharge pipes (not shown). The said pipes 65 are also provided with similar openings x,

which are preferably used for admitting and for drawing off the water.

Auxiliary to the preheating drum 16, I provide another novel heating element consisting of a hollow disc 17, which is positioned concentrically between the bottom of the boiler 9 and the top of the drum 16, and preferably in a plane parallel to said parts. The disc 17 is relatively small in diameter and it is also relatively thin, and contains 75 but a small amount of water as compared with the drum 16. The disc 17 is disposed directly over and concentric to the well 16^c, so that said disc is in direct line and receives the full effect of the heat that passes upwardly through said well. The disc 17 is 80 preferably disposed closer to the top of the drum 16 than to the bottom of the shell 9, and its bottom circumferential edge is formed into a depending flange 17^a, which 85 tends to retard the flow of the products of combustion from its under side towards the bottom of the boiler 9. This close spacing and retardation tends to intensify the heat to such extent that evaporation in the disc 90 17 is effected more readily and quickly than at any other point in the generating system. The disc 17 is connected to the drum 16 for the upward flow of water and steam, by a branch pipe 17^a. By this means the disc 17 95 is continuously supplied with hot water by the drum 16, and this provision combined with the relatively small volume of water contained by the disc, further tends to quicken the evaporation in the disc. The 100 steam or products of evaporation are carried away from the disc 17 through a vertical pipe 18, which taps the disc and extends upwardly in the line of the longitudinal axis of the boiler 9 to a point near its top, which 105 in practice is well above the highest level of the water in the boiler-shell. By this construction and arrangement a portion of the steam which is generated in the drum 16, 110 as well as all of the steam which is generated in the disc 17, is afforded a free and direct passage into the steam space at the top of the shell 9. The pipe 18, having its top end normally open, affords less resistance to the rising steam, than the more tortuous circulatory paths afforded by the pipes 9^e and 14, and enables me to produce steam at relatively high tension in less time, and by the expenditure of less fuel, than is possible by any other boiler construction known 115 to me. By disposing the relatively small and thin disc 17 between the drum 16 and the bottom of the boiler and in the direct path of the heat rising from the well 16^c, 120 my improved boiler is capable of generating steam at a pressure of from 60 to 75 pounds, in not to exceed 15 to 18 minutes, from the time the burner 5 is lit.

The bottom of the boiler shell 9 is preferably provided with a depending annular 130

flange or skirting 9^t, which tends to retard the flow of the products of combustion, thereby intensifying the heat at that end of the boiler. The flange 9^t also tends to deflect 5 a portion of the heat downwardly against the top of the disc 17, before the heat finally passes upwardly around the shell 9. This tends to raise the temperature of the top of the disc 17 and materially quickens the 10 evaporation of the water in said disc.

Having thus described my invention, what I claim as new and desire to secure by Letters Patent, is—

1. In a steam generator, a boiler shell having a steam space at its top, a pipe disposed in the line of the vertical axis of the boiler shell and projecting below the shell, a casing surrounding and spaced from the shell, a burner disposed in a combustion chamber 15 located below the boiler shell, an annular drum disposed directly above the burner, said drum being of less diameter than said chamber, a ring surrounding said drum and connecting said drum with the casing for 20 preventing the upward passage of the products of combustion around said drum, a hollow disk of smaller diameter than said drum disposed concentric and close to the top of said drum above the combustion chamber 25

and being directly heated by the products 30 of combustion which pass upwardly through the opening in said drum, said disk receiving water and steam from said drum and discharging all of its products of evaporation through said pipe into the steam space 35 of the boiler.

2. In a steam generator, a boiler shell adapted to be partially filled with water, a casing surrounding and spaced from said shell, a burner disposed in a combustion 40 chamber below the said shell, an annular drum disposed next above said burner and having a smaller diameter than said combustion chamber, an annular support for 45 said drum, said support closing the annular space between the periphery of said drum and the walls of said chamber, a hollow disc mounted above and receiving water and steam from said drum, said disc being disposed in the direct path of the products of 50 combustion which pass upwardly through the center of said drum, and means for conducting the steam generated in said disc upwardly through the center of the shell and for discharging said steam above the 55 water in said shell.

In testimony whereof I affix my signature.
CHARLES H. LEWIS.
